UNITED STATES PATENT OFFICE.

WILLIAM AUGUSTUS VALENTINE, OF NEW YORK, N. Y.

TICKET-ISSUING APPARATUS.

SPECIFICATION forming part of Letters Patent No. 416,521, dated December 3, 1889.

Application filed August 31, 1888. Serial No. 284,274. (No model.)

To all whom it may concern:

Be it known that I, WILLIAM AUGUSTUS VALENTINE, of the city, county, and State of New York, have invented a new and useful Improvement in Self-Feeding Ticket-Issuing Apparatus, of which the following is a full, true, and exact description, reference being had to the accompanying drawings.

The object of my invention is to provide a self-feeding ticket-issuing apparatus which on the deposit of the proper coin will, at the will of the depositor, produce a ticket-check or other similar article, avoiding the necessity of having a person to attend to or watch the apparatus. Such an apparatus can be used for car-tickets, ferry-tickets, bathing-tickets, and other similar uses.

The apparatus which I here describe has reference more particularly to a self-feeding ticket-issuing apparatus for accident-insurance tickets. Such tickets are shown in Figs. 2, 3, and 4 by dotted lines. The tickets, as will be seen, are perforated transversely and longitudinally. The transverse perforation is for the purpose of allowing a pair of duplicate tickets to be separated from a series, and the longitudinal perforation is for the purpose of allowing the duplicate tickets to be separated, one of which is intended for the depositor of the coin, and the other of which is intended to be returned to the box by hand for the purpose of keeping a record of the transaction.

My invention will be readily understood from the accompanying drawings, in which—

Figure 1 is an isometrical perspective of the case of the self-feeding ticket-issuing apparatus. Fig. 2 is a section taken upon the plane of line $x x$, Fig. 3, looking down upon the apparatus and showing the working mechanism; Fig. 3, a rear end view showing the apparatus at rest. Fig. 4 is also a rear end view showing the apparatus after it has been started. Fig. 5 is a longitudinal sectional elevation upon the plane of the line $y y$, Fig. 3, with the rear lid or cover closed. Fig. 6 is a side elevation of a coin-chute; and Fig. 7 is a section through the center, showing the channel and its projection.

The apparatus is inclosed in the case E. The slot for the deposit of the proper coin is shown at h^2 . This admits the coin to the coin-

chute, which is adapted to coins of a certain size only. If the coin is under the proper size, it will pass out of the coin-chute at h^3 . 55 If it is of the proper size, it will be deposited in the coin-basket A. If it is of the proper weight, it will free the lever B from the recess a in the cam C, formed in the cylinder C on the shaft, which enables the crank d to be 60 turned by the operator.

The lever B is mounted on the standard G² between the forward-projecting arms G G, resting on the knife-edge bar g. The shorter arm of the lever B contains the adjustable weight g', which can be adjusted by means of the set-screw g², so as to be a proper counter-balance for the desired coin. The shorter end of the lever B passes through a slot shown at T, the purpose of which is to assist in locking the end of the lever B which fits into the slot a. In performing its revolution the lever B follows the periphery of the cam C, and the coin-basket is gradually lowered.

The coin-basket is pivotally suspended in the lever B. As the basket is lowered it comes in contact with the trip S, and is turned into the position shown in Fig. 4, when it deposits the coin upon the floor.

The shaft D contains the beveled pinion c. This pinion c works at right angles to the pinion c', which operates the ticket-feed rollers D' D², which are mounted in the bearings A' A², which bearings are fastened to 85 the upper side of the frame E. On the inner end of these rollers D' D² are small gear-wheels d' d².

The tickets are contained in the box I, and pass round the guide-roller J, which is 90 mounted in the bearings attached to the receptacle I, up through the two feed-rollers D' D². One revolution of the crank will produce at the slot K one pair of duplicate tickets.

Upon the shaft D, below the cam C, is a pin F, projecting out so as to strike against the stiff spring f, the purpose of which is to throw back the cam C, so as to leave the end of the lever B free in the slot a.

At the lowest end of the shaft D is attached a ratchet-wheel e, which, together with the pawl e', holds the working parts of the apparatus in any position, thus preventing the

crank d from being turned in the wrong direction.

The object of the gear-wheels $d' d^2$ on the rollers $D' D^2$ is to prevent the tickets from 5 being pulled out continuously, which they accomplish by locking the rollers $D' D^2$.

The coin-basket A is perforated so as to allow any foreign substances—such as shot, sand, or fluids—to fall through. This basket 10 has a lip a' , which rests on the curved end of the releasing lever B, the object of which is to hold the basket in a horizontal position.

The coin-chute H has the slot-channel h . It will be noticed that at a point h' in the passage 15 of the chute it projects beyond the opening h^2 . The reason for this is that a wire cannot be passed through the channel down to the basket A, and thereby release the lever B. The chute H has a slot or rectangular 20 opening in its side wall, so that any coin smaller than the required size will drop out, the side walls of the channel being flared. It has also a long narrow slot h^4 , which is intended to hold any cord, &c., that may be 25 passed through the chute.

The rods L L have fastened to their forward ends hooks $l l$, which catch into eyelets in the cover of the box when the lid E' is closed.

30 What I claim is—

1. The combination, with the mechanism for feeding a strip of paper, of the driving-shaft for the said mechanism, a cam carried thereby having a recess therein, and a lever 35 carrying a coin-basket having one end resting upon the said cam and adapted to enter the said recess when the shaft is in proper position to lock the same and to be moved by the cam as the shaft is turned to discharge 40 the coin, substantially as set forth.

2. The combination of the shaft D, the rollers $D' D^2$, geared with the shaft, which nor-

mally locks them against rotation, the cam on the said shaft, and the locking-lever B, having one end traveling upon the cam and provided 45 with a coin-receiving basket, substantially as set forth.

3. The combination, in a ticket-vending apparatus, of the rollers $D' D^2$, the miter-gears $c c'$, the shaft D, the cam C, the lever B, and 50 the tipping coin-basket A, substantially as described.

4. The combination of the rollers $D' D^2$, the gears $d' d^2$, the miter-gears $c c'$, the shaft D, provided with rotatory mechanism d , and the 55 lock for the shaft D, whereby the rollers $D' D^2$ are prevented from rotation excepting on the rotation of the shaft D, substantially as described.

5. The inclined chute H, provided with the 60 discharge-slot for coins of small size, and the narrow slot h^4 adjacent to the discharge end of the receiver, substantially as and for the purpose set forth.

6. In a vending apparatus, the lever B, provided with a curved end, in combination with the coin-basket A, pivoted in the curved end of the lever B, and provided with a lip a' for holding it in a horizontal position, and a stationary trip with which the coin-basket engages as the lever is depressed, substantially 70 as set forth.

7. The counterbalanced lever B, having a curved outer end, a coin-receiving basket A, having perforations in its bottom and pivoted 75 in the curved end of the lever, and a trip for the basket, substantially as set forth.

In testimony whereof I have signed my name to this specification in the presence of two subscribing witnesses.

WILLIAM AUGUSTUS VALENTINE.
